UNITED STATES PATENT OFFICE.

EDWARD J. FLOYD, OF DOUGLAS, GEORGIA.

COMBINATION-CHAIR.

1,229,251.

Specification of Letters Patent. Patented June 12, 1917.

Application filed January 5, 1916. Serial No. 70,524.

To all whom it may concern:

Be it known that I, EDWARD J. FLOYD, a citizen of the United States, residing at Douglas, in the county of Coffee and State 5 of Georgia, have invented certain new and useful Improvements in Combination-Chairs, of which the following is a specification.

This invention has relation to certain new 10 and useful improvements in combination chairs, and has for its primary object the provision of a chair which may be readily converted into a cot when desired.

The invention has for another object, the 15 provision of a chair of this character in which the back will be adjustable with respect to the seat and a foot rest depending from the free edge of the seat may also be adjusted with respect to the latter.

20 The invention has for another object, the provision of a chair of the above-stated character which may also include arms carried by the seat, a leaf pivoted to one of the arms, and a drawer beneath the seat for receiving toilet articles and the like.

25 The invention has for a still further object, the provision of a chair of this character which will be of simple construction and cheap to manufacture, as well as highly 30 efficient in use.

With the above and other objects in view, the invention resides in the novel construction, combination, and arrangement of parts as hereinafter set forth in the specification, 35 pointed out in the claims, and shown in the drawings, in which—

Figure 1 is a side elevation of the chair;

Fig. 2 is a front elevation of the same;

40 Fig. 3 is a vertical section through the complete chair;

Fig. 4 is a rear elevation of the same;

Fig. 5 is a side elevational view of the chair adjusted for use as a cot or crib;

45 Fig. 6 is a transverse detail section on the line on 6—6 of Fig. 5, looking in the direction indicated by the arrow.

Referring more particularly to the drawings in which similar reference characters designate corresponding parts throughout the several views, 1 designates the rockers to which are secured the side standards 2 arranged in pairs and having mounted upon their upper ends the arms 3. It will be understood that the standards 2 are connected 50 near their lower ends by the longitudinal

cross pieces 4 and transverse cross pieces 5. Outer longitudinal supporting strips 6 are also secured to the standards 2 and the longitudinal frame members 7 of the back are pivoted to the projecting rear ends of 60 said supporting strip 6, as shown at 8. The longitudinal side strips 7 of the frame for the back are connected at their upper ends by a suitable top cross member 9 and are braced by a transverse brace bar 10 65 extended through said longitudinal side strips 7.

The side members 11 of the foot-rest 12 are mounted upon a suitable supporting rod 13 extended through the forward projecting 70 ends of the supporting strips 6 and the foot-rest 12 is adapted to be retained in its adjusted inclined positions by means of a pivoted latch member 14 carried by the same and having suitable teeth 15 for engagement 75 with one edge of one of the front transverse members 5. When the latch member 14 is not in use, however, it extends beneath the drawer 16 which rests upon the longitudinal members 4 and is adapted to be 80 withdrawn from one side of the chair, as will be readily understood by referring to the drawings.

The seat and the body of the back of the chair, as well as the back of the foot-rest 85 12, are formed of a single strip of canvas 17 or the like having one end secured to the body or main portion of the foot-rest 12. This will be readily understood by referring to Fig. 3 of the drawings. 90

The back may be readily secured in its vertical position or in a slightly inclined position by means of the hooks 18 carried by the longitudinal back frame members 7 and adapted for engagement in the members 19 carried by the arms 3 and also by the standards 2.

When it is desired to use the chair as a crib or cot, however, the hooks 18 are released, and the pins 20 projecting from the outer faces of the back longitudinal side members 7 are engaged in the proper notch 21 in the side of the parallel supporting members 22. The parallel supporting members 22 are connected at their lower portions 105 by the transverse rods 23, upon one of which is mounted a swinging member 24 having notches 25 forming in one face for engagement with the transverse member 26 extended across the rear ends of the rockers 1. 110

This will form a secure support for the back of the chair when lowered.

By referring to Fig. 5, it may be readily understood how the chair may be converted into a crib or cot and the back and foot-rest supported in horizontal position.

By referring to Fig. 1, it will also be seen how the mirror 27 normally supported above the chair back may be brought to position in front of the party sitting in the chair. The mirror 27 is adjustably mounted, as shown at 28, upon the offset portion 29 of a rod 30 which has its opposite ends bent and engaged against the outer faces 15 of the back longitudinal frame members 7 and mounted upon the pivot pins 31 projecting from the latter. The rod 30 normally rests against the pins 20 previously mentioned and the rod 30 and mirror 27 20 are prevented from swinging over the front edge of the chair back, by the pivoted stop members 32 secured to the front of the chair back at the upper edge of the same. By turning the pivoted stop members 32 to one 25 side, however, the rod 30 and mirror 27 may be brought to position in front of the party sitting in the chair as indicated by dotted lines in Fig. 1.

A leaf 33 is pivoted, as shown at 34, to 30 one arm 3 of the chair and adapted to either rest against one side of the chair, as shown in Fig. 5, or extend across the arms 3, as shown in Figs. 1, 2 and 3. It will be evident that the leaf 33 may be provided with a 35 ruled edge and a checker-board may be marked upon the same, if desired. It will furthermore be apparent that the leaf may serve as a table, a book rest or a typewriter stand, and, in fact, may serve various purposes. It will also be understood that the 40

drawer may serve to hold toilet articles and other objects.

While the preferred embodiments of the invention have been shown and described, it will be understood that minor changes 45 in the details of construction, and arrangement of parts may be resorted to within the scope of the appended claims without departing from the spirit of the invention or sacrificing any of the advantages of the 50 same.

What is claimed is:

1. In a chair, a frame having a seat thereon and further provided with a transversely extending locking bar, a hinged back connected with the frame and capable of assuming a horizontal position, pins extending laterally from the side bars of the back, supporting legs having notches therein to accommodate the pins on the back when in a 60 horizontal position, locking members pivotally connected with the supporting legs and adapted for engagement with the transverse locking bar to retain the supporting legs and frame against movement with respect to each other.

2. The combination with a chair having a hinged back thereon capable of being supported in vertical and horizontal positions, of rods pivotally connected upon the opposite sides of the back, and a mirror carried by the rods, said mirror constituting a headrest when the back is arranged in a horizontal position.

In testimony whereof I affix my signature 75 in presence of two witnesses.

EDWARD J. FLOYD.

Witnesses:

C. A. FURNEY,
J. R. VICKERS.
